REVERSIBLE FEEDING MECHANISM

Richard H. Colby, South Hadley, Mass., assignor to the United States of America as represented by the Secretary of the Army

Filed June 14, 1954, Ser. No. 436,748

5 Claims. (Cl. 89—33)

(Granted under Title 35, U.S. Code (1952), sec. 266)

The invention described herein may be manufactured and used by or for the Government for governmental purposes without the payment of any royalty thereon.

My invention relates to a recoil-operated firearm and more particularly to a feeder therefor.

The receiver of a recoil-operated weapon includes a guideway for directing therein a disintegrating cartridge belt having open links for securing cartridges. The guideway is provided with means for stopping the feeding advance of the belt in position to permit stripping of the leading cartridge therefrom and the weapon includes a rammer for operating through the stripping position responsive to the recoil cycle of the weapon. In the forward stroke thereof, the rammer engages the base of the cartridge to strip the cartridge from the belt and chamber the cartridge in the barrel of the weapon. It is an object of my invention, therefore, to provide a simple and reliable device for feeding an ammunition belt to the stripping position of a weapon and for guiding the links of the belt from the stripping position.

Another object of my invention is to provide a device for selective right- and left-hand feed of an ammunition belt to the weapon.

A further object of my invention is to provide a feeder for a weapon constructed for easy and rapid change of feed direction.

An additional object of my invention is to provide a feeder removably attachable to the weapon for ready access to the interior of the receiver.

A still further object of my invention is to provide such a feeder having a removable cover for immediate access to the ammunition belt.

It is also an object of my invention to provide a feeder with a removable cover for including the actuating mechanism of the feeder.

In carrying out my invention, a weapon having a barrel assembly operable in recoil reciprocation and a rammer operable through a cartridge stripping position for ramming cartridges from an open link ammunition belt into the barrel of the weapon responsive to the reciprocation, is provided with a device for feeding the ammunition belt to the stripping position including a tray disposed laterally subjacent the stripping position for supporting the ammunition belt and a removable cover therefor. The cover includes a feed slide slidably secured therein by an axially disposed support bar and a cam plate axially slidably in the cover is provided with a cam track engageable with a cam follower depending from the slide. The cam plate is secured to the barrel assembly to actuate the slide in reciprocal lateral movement responsive to the reciprocation of the barrel assembly.

A pawl is pivoted on the slide and spring-biased to a normal position for engagement to propel the lead cartridge of the belt to the stripping position as the slide moves in one direction and for riding over the following cartridge as the slide moves in the opposite direction. A cartridge depressor is resiliently mounted in the underside

2

of the support bar and is provided with a beveled surface for guiding the lead cartridge to a stripping position thereunder and the under surface of the depressor is concave to retain the cartridge in the stripping position.

5 A cartridge belt stop is provided for guiding the belt links from the stripping position and a spring-biased pawl retains the belt against retrograde movement on the tray.

For a more complete understanding of my invention, reference is directed to the following explanation and the 10 accompanying drawings in which:

Fig. 1 is a partial elevational view of a weapon incorporating my invention with the barrel extension and the rammer shown in the rearward positions;

15 Fig. 2 is an enlarged view along the line 2—2 of Fig. 1;

Fig. 3 is a perspective view of the combined cartridge belt stop and link guide-way of the weapon;

Fig. 4 is a view along the line 4—4 of Fig. 1;

Fig. 5 is a partly cutaway perspective view of the feed portion of the weapon;

20 Fig. 6 is a partial view of Fig. 2 with an alternate ammunition retaining device;

Fig. 7 is an enlarged cutaway view of the cartridge belt feeding and retaining pawls shown in Fig. 6;

Fig. 8 is a sectional view of another form of my invention with permanently attached cartridge retaining pawls; and

25 Fig. 9 is a perspective view of the form shown in Fig. 8.

According to the drawings a recoil-operated weapon 12 includes a receiver 14 and a barrel assembly including an 30 extension 18 slidably disposed and biased to a battery position thereon.

35 A feed tray 20 is transversely disposed on receiver 14 for lateral support of a belt 22 for feeding cartridges 24 to weapon 12. Belt 22 is of the disintegrating type and cartridges 24 are connected therein by links 25. Tray 20 includes a centrally disposed longitudinal slot 26. A bolt (not shown) is slidably disposed for accelerated reciprocal movement with respect to the barrel assembly includes a rammer 28 for extending through the slot.

40 A substantially flat cover 29 includes sides 30 with depending tabs 31 adjacent the front and rear ends thereof. Tray 20 is provided with a pair of similar tabs 32 on either side thereof. Axial rods 33 are slidably disposed in projections 34 on either side of receiver 14 and biased

45 to normal positions therein by springs 35 to project through corresponding diameter holes 36 of tabs 31 and 32 to secure tray 20 and cover 29 to receiver 14. Tabs 31 and 32 are open along the underside thereof to form slots 38 with parallel sides spaced at a distance less than the diameter of rods 33. Rods 33 are provided with slabbed portions 40 having a width slightly less than that of slots 38. In order to unfasten tray 20 and cover 29 from receiver 14 rods 33 are moved forwardly against the bias of springs 35 to align slabbed portions 40 with slots 38 and permit disengagement of tabs 31 or 32 or both from rods 33.

50 A rectangular housing 41 includes a boss 42 for projecting upwardly into a lateral slot 43 in cover 29 and a slide 44 is slidably disposed in opposed channels within housing 41. Housing 41 fits into a lateral groove 45 formed in the top of a longitudinal support bar 46 which is in turn secured to cover 29 by a pair of retainers 47 located adjacent the front and rear ends thereof. Each of the 55 retainers 47 includes a rotatable stem with a hand knob 48 projecting from cover 29. Heads 49 included on the lower ends of retainers 47 are of rectangular section for projecting through corresponding slots in support bar 46 and such retainers are rotated to secure support bar 46 to cover 29. A biasing spring 50 is provided between

60 knob 48 and cover 29 to prevent accidental unfastening of retainers 47. A pair of upwardly projecting spaced-apart lugs 52 are provided on the top of support bar 46

at the front and rear ends thereof and are arranged to extend through lateral grooves 54 in cover 29. The ends of bar 46 are vertically slotted as shown at 120 and a transverse slot 122 is formed in the underside of bar 46 at right angles to slot 120. When retainer 47 is rotated so that head 49 thereon fits into slot 122, bar 46 serves to lock feed slide housing 41 to cover 29. In order to remove housing 41 from cover 29, each retainer 47 is first depressed against spring 50 to remove head 49 from slot 122 and then rotated so that upon release thereof head 49 can be moved upwardly through vertical slot 120 to unfasten bar 46 from cover 29.

Receiver 14 is interiorly and oppositely grooved as shown at 60 in Fig. 2 while bar 46 is correspondingly grooved on either side thereof as shown at 58 to permit slide operation of a cam plate 62 therein for right- and left-hand feed of weapon 12. The front end of barrel extension 18 is provided with symmetrically disposed studs 64 and 66 for respective engagement with a laterally elongated slot 70 of cam plate 62 for imparting reciprocal axial movement thereto responsive to the recoil cycle of the barrel assembly.

Slide 44 is provided with a cam follower 72 and a bracket 74 projecting downward from opposite ends thereof. Cam follower 72 engages in a longitudinally extending cam track 76 provided in cam plate 62 and bracket 74 provides axial pivotal support for a pawl 78. The surfaces of cam track 76 are formed for reciprocal lateral operation of slide 44 responsive to the recoil and counter-recoil strokes of the barrel assembly. Studs 64 and 66 engage cam plate 62 for right- and left-hand feeds, respectively.

Pawl 78 is biased by a spring 79 to a normal position for engagement to successively feed the lead cartridges of belt 22 into a stripping position 80 directly above slot 26 responsive to the lateral operation. A depressor 81 is slidably disposed above the stripping position and is downwardly biased in support bar 46 by a spring 82. Under surface 84 of the depressor is concave for retaining a cartridge in the stripping position and opposite edges 86 are beveled to produce an upward camming movement of depressor 81 which will compress spring 82 as the leading cartridge 24 is fed into the stripping position thereof by pawl 78.

Opposite edges of tray 20 include notches 83 and the tray is provided with brackets 87 adjacent the notches having lateral surfaces 88. A pawl 90 is pivoted on the appropriate surface 88 and biased by a spring 85 to engage a cartridge 24 in belt 22 and restrain the belt against retrograde movement on the tray.

When the lead cartridge is stripped from belt 22 by forward movement of rammer 28, the link holding the lead cartridge separates from the belt and the succeeding cartridge becomes the new lead cartridge with pawl 90 holding the new lead and following cartridges in position on tray 20.

In the counterrecoil stroke of the barrel assembly, slide 44 moves pawl 78 away from stripping position 80 and pawl 78 pivots to ride over the new lead cartridge.

A combined cartridge belt stop and link guide 92 includes mutually perpendicular legs 94 and 96 with similar tongues 98 and 100 projecting therefrom for engagement with tray 20. Cartridge belt stop 92 is secured on tray 20 with tongue 98 projecting into a slot 102 of the tray appropriate to the direction of feed and tongue 100 projecting into a similar slot (not shown) adjacent the stripping position. Arcuate edges 103 are formed on either end of belt stop 92 to stop belt 22 with the lead cartridge thereof in the stripping position.

A distinct advantage of the construction described above is realized in the ease with which the direction of feed is reversed. To reverse the direction of feed, retainers 47 are removed from the weapon, housing 41 is reversed in bar 46, cam plate 62 and engaged in the other set of grooves 58 and 60 with slot 70 engaging stud 66,

and support bar 46 is again secured to cover 29 by means of retainers 47. Pawl 90 is pivoted on the opposite bracket 87, cartridge belt stop 92 is secured to the opposite side of tray 20.

A first alternate construction for retaining an ammunition belt 22 on tray 20 is shown in Figs. 6 and 7 for use with cartridge belt stop 92. Housing 41 is provided with symmetrically disposed depending lugs 104. Lugs 104 are bifurcated and pawls 106 are pivoted therein and biased by springs 108 to engage the succeeding cartridge 110 when the lead cartridge 112 is propelled by actuating pawl 78 to the stripping position. As shown in Fig. 7, pawl 78 moves between pawls 106 as it advances succeeding cartridge 110 to the stripping position.

A second alternate method of retaining an ammunition belt on tray 20 is shown in Figs. 8 and 9 for use with cartridge belt stop 92. A pair of pawls 114 are similarly pivoted and spring-biased on tray 20 and the pawls include projections 116 operating in cuts 118 in the tray for engagement with cartridge belt stop 92. As cartridge belt stop 92 is mounted on the tray, the corresponding pawl is depressed to the level of the tray surface and thereby inactivated so that the belt 22 is retained against retrograde movement on tray 20 by the remaining pawl 114.

It is readily seen that both of the alternate constructions eliminate the step of changing the position of tray-mounted pawls in reversing the direction of weapon feed. In addition, the first alternate construction is of particular advantage because pawls 106 engage succeeding cartridge 110, and thereby permit the last cartridge of a belt to be fired in the weapon.

Although a particular embodiment of the invention has been described in detail herein, it is evident that many variations may be devised within the spirit and scope thereof and the following claims are intended to include such variations.

I claim:

1. In a firearm having a receiver, a barrel slidably disposed in the receiver for recoil and counterrecoil, and a cover associated with the receiver to form a feedway for the transverse passage therethrough of a belt of linked cartridges, a reversible feed mechanism comprising a substantially rectangular reversible housing releasably secured to the underside of the cover in coaxial relation with the feedway, a longitudinal bar releasably secured to the underside of the cover adjacent the front and rear ends thereof to lock said housing thereto, a feed slide slidably mounted in said housing, said slide having a cam follower depending from one end thereof and a resiliently mounted feed pawl depending from the opposite end thereof, said locking bar having a groove extending along each of opposite longitudinal sides thereof, the cover having depending opposite sides and a groove extending longitudinally along the interior surfaces of each of said sides respectively opposite and parallel to said grooves in said locking bar to form right and left hand sets of grooves, a cam plate slidably disposed in said set of grooves furthest from said feed pawl, said cam plate having a longitudinally extending cam track therein engageable with the lower end of said cam follower on said slide, means for releasably securing said cam plate to the barrel for reciprocation therewith, said cam track having an angular central camming portion for moving said cam follower in a plane normal to the longitudinal axis of the receiver whereby said slide and said feed pawl thereon are actuated to feed the cartridge belt along the feedway during each firing cycle of the gun, means releasably secured in the feedway in the path of the cartridge belt to stop the leading cartridge thereof in position to be chambered in the barrel, and means for releasably securing both sides of the cover to the receiver whereby the release of either side permits the cover to be pivoted about the opposite side thereof and

thereby provide ready access to the feed mechanism for reversing the direction of operation thereof.

2. The combination defined in claim 1 wherein said last-mentioned means comprises a pair of spaced-apart tabs depending from each of said depending sides on the cover, a pair of lateral projections extending outwardly from the receiver to releasably receive each of said tabs on the cover, each of said pairs of projections and said tab therebetween on either side of the gun having axially aligned holes therethrough, a rod slidably mounted through said projections and said tabs on either side of the gun to secure the cover to the receiver, each of said receiver projections having a vertical slot in the bottom thereof in communication with said hole therein and of lesser width than the diameter of said rod projecting therethrough, each of said rods having oppositely slabbed areas of lesser width than said vertical slots in said cover tabs, and resilient means seated in the forwardmost receiver projection against the forward end of said rod therein to normally urge said rod rearwardly in order to maintain said slabbed portions thereon out of alignment with said slots in said cover tabs and thereby provide a fulcrum for pivotal movement of the cover when the opposite side thereof is released from the receiver.

3. In a firearm having a receiver, a barrel slidably disposed in the receiver for recoil and countercoil, and a cover associated with the receiver to form a feedway for the transverse passage therethrough of a belt of linked cartridges, a reversible feed mechanism comprising a feed tray in the feedway, a reversible housing having a channel-shaped opening in the underside thereof and being releasably mounted to the cover in coaxial alignment with said feed tray, a longitudinal bar having a transverse channel for receiving said reversible housing, means for releasably securing said bar to the cover adjacent the front and rear ends thereof to lock said housing thereto, a feed slide mounted in said housing for reciprocal movement therein, said slide having a cam follower depending from one end thereof and a depending feed pawl pivotally mounted to the opposite end thereof, spring means for normally urging said feed pawl downwardly into the feeding path of the cartridge belt, means releasably secured to said feed tray in the path of the cartridge belt to stop the leading cartridge thereof in position to be stripped from the links, means in said feed tray for releasably holding the cartridge belt against movement in a direction opposite the feeding path thereof, a symmetrical cartridge depressor resiliently mounted in said longitudinal bar to depend from the underside thereof and hold the leading cartridge belt link against forward movement during the stripping of the cartridge therefrom, said locking bar having a longitudinal groove extending along each of the opposite sides thereof, the cover having opposed depending sides and a groove extending longitudinally along the interior surfaces of each of said sides respectively opposite and parallel to said

grooves in said locking bar to form right and left hand sets, a cam plate slidably disposed in said set of grooves furthest from said feed pawl, said cam plate having a longitudinally extending cam track therein engageable with the lower end of said cam follower on said slide, means for releasably connecting the rear end of said cam plate to the barrel for reciprocation therewith, said cam track having an angular central camming portion for moving said cam follower in a plane normal to the longitudinal axis of the receiver whereby said slide and said feed pawl are actuated to feed the cartridge belt along said feed tray during each firing cycle of the gun, and means for releasably securing both sides of said feed tray and the corresponding sides of the cover to the receiver whereby the release of either of said securing means permits said tray to be pivoted about said securing means on the opposite side of the receiver to provide access to the breech end of the barrel and simultaneously permits the cover to be pivoted in the same direction to expose said feed tray and permit the relocation of the components of the feed mechanism required to change the direction in which the cartridges are fed into the gun.

4. The combination defined in claim 3 wherein said means for releasably holding the cartridge belt on said feed tray against movement in the direction opposite the feeding path thereof comprises a belt holding pawl resiliently mounted in either end of said feed tray and arranged to be depressed by the underside of said cartridge belt stop whereby only one of said belt holding pawls is in engagement with the cartridge belt at any given time.

5. The combination defined in claim 3 wherein said feed slide housing includes a pair of depending lugs at one end thereof and said means for releasably holding the cartridge belt on said feed tray against retrograde movement comprises a pawl pivotally mounted to each of said lugs on said feed slide housing and sufficiently spaced apart to permit the passage of said feed pawl therebetween during the reciprocation of said slide.
